DESIGN FOR A DESK TRAY

David Cunningham, Fort Wayne, Ind., assignor to Tokheim Oil Tank and Pump Company, Fort Wayne, Ind., a corporation of Indiana

Application March 16, 1945, Serial No. 118,525

Term of patent 14 years

(Cl. D74—1)

To all whom it may concern:

Be it known that I, David Cunningham, a citizen of the United States, residing at Fort Wayne, Allen County, Indiana, have invented a new, original, and ornamental Design for a Desk Tray, of which the following is a specification, reference being made to the accompanying drawing, forming a part thereof.

The figure is a front perspective view of a desk tray, showing my new design.

The back of the design is plain and the opposite side presents substantially a similar appearance as the side shown.

I claim:

The ornamental design for a desk tray, substantially as shown and described.

DAVID CUNNINGHAM.
